(57) **CLAIM**

The ornamental design for a display screen or portion thereof with transitional graphical user interface, as shown and described.

DESCRIPTION

FIG. 1 is a front view of a first image in a sequence according to a first embodiment of our design for a display screen or portion thereof with transitional graphical user interface;

FIG. 2 is a front view of a second image in the sequence thereof;

FIG. 3 is a front view of a first image in a sequence according to a second embodiment of our design for a display screen or portion thereof with transitional graphical user interface; and,

FIG. 4 is a front view of a second image in the sequence thereof.

The appearance of the claimed design transitions between the images shown in FIGS. 1 to 2 and between the images shown in FIGS. 3 through 4. The process or period in which one image transitions to another forms no part of the claimed design.

The outer broken line rounded rectangles showing a device, the broken line rectangle showing the display screen or portion thereof, and all other broken lines showing portions of the graphical user interface form no part of the claimed design.
